REMOTE-CONTROL APPARATUS WITH
ADJUSTABLE GAPMichel N. Yardeny and Robert Bernas, New York,
N. Y.; said Bernas assignor to said Yardeny

Application August 22, 1945, Serial No. 612,042

7 Claims. (Cl. 200—11)

1

This invention relates to remote control apparatus for positioning from a control point a load at a remote point by controlling the energization of a load motor at the remote point.

Apparatus of this class generally includes a pair of conducting elements spaced by a gap and engageable by a contact arm which engages the respective conducting elements for directional rotation of the load motor and is aligned at the gap separating them to stop motor rotation. One of the said two pairs of relatively movable members is manually adjusted to cause directional rotation of the load motor by displacing the gap and the contact arm, and the other member is turned by a pilot motor at the control point in a direction to cause alignment of the gap and contact arm to stop rotation of the load motor with the load at the desired position.

One of the difficult problems in apparatus of this class is to prevent the contact arm from over-running the point of alignment with the gap and engaging the anterior conducting element to cause reversal of motor rotation; this over-running is repeated in the opposite direction and results in undesirable "hunting." The extent of over-running depends, in addition, to other factors, upon the size and proportion of the gap and its relation to the contact element of the contact arm.

One of the objects of this invention is to provide an apparatus of the class described, means for adjusting the size of the gap relative to the contact element, for the purpose of eliminating over-running and "hunting."

It has been found that the contact element of the contact arm frequently wears grooves in the conducting elements. A further object of the invention is to provide adjustability of the contact arm so that it may be adjusted to engage fresh, unmarred surfaces of the conducting elements.

In remote control apparatus of the class described, the gap and contact element of the contact arm may be arranged so that when the two are brought into alignment, as explained above, to stop motor rotation, the contact element may engage both adjacent conducting elements (referred to as "bridging the gap") or may be received in a space defined by the gap, without contacting either of the adjacent conducting elements (referred to as "non-bridging").

A further object of the invention is to provide adjustment between the gap and the contact arm which will enable the device to be made either "bridging" or "non-bridging."

2

Another object of this invention is to provide an adjustable gap for the purposes stated above, in conjunction with control apparatus which is implemented with a reduced speed provision.

5 For the attainment of the foregoing and such other objects as may appear or be used herein, there is shown embodiments of the invention in the accompanying drawings, wherein:

10 Fig. 1 is a diagrammatic illustration of a typical remote control system provided with the improved, adjustable gap alignment of this invention, and structurally showing in front view, the gap adjusting means;

15 Fig. 2 is a sectional view through the improved control device, in a reduced scale, with a modified showing of the collector rings of the diagrammatic illustration of Fig. 1;

20 Fig. 3 is a detail top view of the contact arm of the improved device; and

25 Fig. 4 is a front view of a modified form of adjustable gap arrangement.

Referring first to Fig. 1, the control device briefly outlined in the statement of invention comprises a pair of relatively movable members, 25 one of which is a base preferably in the form of an insulated disc 10 rotatably mounted on a spindle 9 and carrying a pair of electrical conducting elements in the form of segments 11, 12, the adjacent ends of which are spaced by a gap

30 8. The other member of the said pair of relatively movable members is a contact arm 20 which is mounted on the spindle 9 and carries at its distal end a contact element 21, which is preferably in the shape of a ball, as best shown in Fig. 2. Contact element 21 is engageable with the conducting segments 11, 12 to cause—as outlined above, directional rotation of the load motor—designated 50 in Fig. 1, and is receivable in the gap 8, to stop motor rotation (as will be more fully described).

35 Conducting elements 11, 12 are connected to collector rings, respectively, 13, 14, which are engaged by stationary brushes, respectively, 15, 16 connected by leads 17, 18 to the terminal ends 40 of the field windings 47, 48 of a pilot motor 40 and further connected by leads 17^x, 18^x to the terminal ends of field windings 57, 58 of a load motor 50. The common terminal of reversing field windings 47, 48 of the pilot motor is connected by a short lead 41 to the armature of the load motor and through a short lead 41^x to a lead 42 leading to a contact 75 normally engaged by an armature 74 of relay 70, the proximal end of which is connected by a short lead 74^x to a wire 55 7 connected through switch 7s to one terminal

' of the source of current supply. The other supply terminal 8' is connected through switch 8s and a lead 8 to the proximal point of the contact arm 20 at the spindle 8. The common terminal of field windings 57, 58 and load motor 50 is connected through a short lead 51, to the armature of the motor, from whence lead 52 connects to the aforesaid supply wire 7.

In the form shown in Fig. 1, the contact arm 20 is selectively adjusted, by manipulation of a knob 5 secured to spindle 8, to cause directional rotation of load motor, (as previously outlined in the statement of invention), and the insulated disc 10 is moved in a direction to bring the contact element 21 and gap 8 into alignment to stop motor rotation. For this purpose, there is secured a shaft 43 of the pilot motor a pinion 43g which meshes with a gear 10g secured to rotate with the insulated disc. Displacement of contact element 21 of contact arm 20 away from the gap 8, and engagement therewith with one of the conducting elements 11, 12 will cause the circuit to be completed to both the load motor 50 and the pilot motor 40, which circuit may be traced, assuming that the engagement of the contact arm 20 is with the conducting element 11 from one terminal 8' of the source of supply through lead 8, to the proximal point of the contact arm 20, through the contact arm to the engaged segment 11, its collector ring 13, brush 15, lead 17, to field winding 41 of the pilot motor 40, from whence through short lead 41, through the armature of the motor, through short lead 41x and lead 42, to contact 75, unattracted armature 74 (as shown in Fig. 1) of normally de-energized relay 70, short lead 74x to the other supply wire 7. Concurrently, a circuit is completed through the corresponding winding 57 of load motor 50, which may be traced through lead 17x, field winding 57, short lead 51, through the armature of load motor 50, and through lead 52, to the said supply wire 7. Energization of field winding 57 of the load motor causes clock-wise rotation to move the load at the remote point, while energization of the corresponding field winding 41 of the pilot motor energizes the pilot motor for rotation in a clockwise rotation, to cause, through the connecting gears 43g and 10g, turning of the insulated disc 10 in a counter-clockwise direction to bring gap 8 into alignment with the contact element 21 of the adjustable contact arm 20, whereat the afore-traced circuit of field winding of the pilot motor and load motor is broken and motor rotation stopped.

The aforementioned relay 70 is used in connection with the means provided for reducing the speed of pilot motor rotation when alignment between gap 8 and contact element 21 is approached; where such a provision is omitted, lead 42 would connect directly to supply wire 7. The speed governor for reducing speed of the pilot motor is designated generally 60, and the component parts thereof are mounted on an insulated disc 61 secured to rotate with shaft 41 of the pilot motor. These component parts comprise a swing arm 62 pivotally mounted on the disc 61 at 63 and provided at its distal end with a contact 64 which is engageable with the contact 66 secured on the insulated disc 61. The proximal end of swing arm 62 is connected to a collector ring 65, and the fixed contact 66 is connected to a collector ring 68, which collector rings are engaged by stationary brushes, respectively: 67, which is connected by lead 69 to the supply wire 7, and by a brush 46, which is connected by a short

lead, as shown, to the lead 42. Swing arm 62 is provided with a weight, so that centrifugal force will be effective to break contact between 64 and 66 when the high limit of speed is attained. The speed governor 60 is effective to reduce the speed of motor rotation, only at such times when alignment between gap 8 and contact element 21 is approached, and by-passed at other times, so that the speed of pilot motor rotation will not be limited. This by-passing of the governor 60 is under control of the afore-mentioned relay 70 and an auxiliary contact arm 30, which is secured to rotate with the contact arm 20. Auxiliary contact arm 30 is provided at its distal end with a contact 31 which may also be in the form of a sphere, as shown in Fig. 2, engageable with a short conducting plate 79 which, as shown in Fig. 1, is substantially diametrically opposite to the gap 8. Conducting plate 79 is connected to a collector ring 78 which is engaged by a stationary brush 77 connected by a lead 72 to one terminal of the aforementioned relay 70, the other terminal being connected by a short lead 71 to the supply wire 7.

When contact element 31 of auxiliary contact arm 30 is not in engagement with the conducting plate 79, the circuit from one supply terminal 8', through lead 8, to the proximal end of the contact arm, to the relay 70, is broken; hence, at such times, other than when the auxiliary arm engages the conducting plate 79, the armature 74 of relay 70 will be in engaging position, as shown in Fig. 1, with contact 75, thus completing the circuit from the armature of the pilot motor directly to supply wire 7 and thus by-passing the speed governor 60. When engagement is made between the auxiliary contact arm 30 and the conducting plate 79 the circuit through relay 70 will be completed, the relay energized and its armature 74 attracted away from engagement with contact 75, thus breaking the by-passing circuit and causing the circuit through the pilot motor to pass through the speed governor, which circuit may be traced through brush 46, collector ring 65, to the proximal end 63 of the swing arm 62, the distal contact 64, stationary contact 66 (assuming that the speed of the motor rotation is below the upper limit) to collector ring 68, brush 67, lead 69, to the supply wire 7.

Even with the provision of reduced speed, when the alignment between gap and conducting arm is approached, there is a tendency of the insulated disc 10 turned by the pilot motor 40, as described, to over-run the position of alignment, thus causing contact element 21 to engage with the other of the conducting segments 11, 12 which causes the motor to start rotating in the opposite direction; the insulated disc may again over-run in the opposite direction, thus causing objectionable hunting back-and-forth. One way which objectionable hunting may be avoided is by increasing the size of the gap, or, rather, the clearance separating the adjacent ends of the conducting elements. But this is open to another drawback resulting from the fact that there may be loss in accuracy in load positioning because the contact element of the contact arm will be positioned at undetermined points in the gap. We have discovered that the two objections mentioned above (over-running by reason of a narrow gap and inaccurate positioning, because of the wide gap) may be compromised by making the gap adjustable, so that by trial and error the proper gap distance may be determined and the apparatus fixed with the best gap distance to meet both conditions men-

tioned above. This is accomplished by tapering the gap, as best shown in Fig. 1, and mounting the contact arm 20, so that it can be radially adjusted to position its distal contact element 21 at different radial distances from the center of the spindle 9. For example, in the form illustrated in Fig. 1, if the contact arm 20 is adjusted to position its contact element 21 relatively nearer the spindle 9, the path of the gap traversed by contact element 21 will be less than the gap traversed were the contact arm 20 adjusted away from spindle 9. In this manner, the gap traverse may be selected by trial and error until the best traverse or gap opening is found.

Contact arm 20 is made adjustable for the aforesaid radial movement in any suitable manner; as shown in Figs. 1 and 3, the proximal end of the contact arm 20 is bifurcated to form a central recess 22 separating fingers 23, 24 and in each of the fingers is provided an elongated slot, respectively 23^x, 24^x, as best shown in Fig. 3. In mounting the bifurcated contact arm on the insulated disc 10, the spindle 9 is received in the recess 22, as best shown in Fig. 1 and the contact arm is secured to rotate with spindle 9 by suitable fastening means, for example, screw 25, as shown, the shanks of which pass through the elongated slots 23^x, 24^x, and are threaded into a collar or flange 6, integral with or secured to the spindle 9.

The auxiliary contact arm 30, used as already described above for the reduced speed provision, may be simultaneously radially adjusted relative to spindle 9. Cooperative therewith, the conducting plate 79 is likewise provided with a taper, to provide different traverse for the contact element 31 of the auxiliary contact arm. The purpose of providing the different engaging traverse between the contact element 31 and conducting plate 79 is to regulate the time of their engagement and thus to vary the time that the relay 70 is energized to call the rotary governor 60 into operation as alignment between gap 8 and contact arm 20 is approached and reached.

A further object in providing a radial adjustment of contact arm 20 is to be able to change the position of its contact element radially, so that it may traverse circles of different radii. This is desirable because the contact element 21 very frequently wears grooves in the conducting elements or segments 11, 12; by changing the radial position of the contact element 21, it may be caused to engage fresh, unmarred surfaces of the conducting elements.

Still another object in providing the aforescribed adjustment of the gap 8 is that the contact element 21 may be made, by radially positioning its contact arm 20, to either bridge the gap 8—by which is meant to simultaneously engage the adjacent conducting elements 11, 12—or to be aligned in the gap 8 without engaging either of the segments 11, 12. In the form shown in Fig. 1, the bridging position of the contact element 21 would be the position in which the contact arm 20 is adjusted towards spindle 9; the other, or non-bridging position, would be the position of contact element 21 when its contact arm 20 is adjusted away from the spindle 9.

A second form in which the contact arm may be adjusted to position its contact element 21 at different radial distances is shown in Fig. 4, where the corresponding parts bear reference characters identical to those shown in Fig. 1. Secured to rotate with the spindle 9 is a lever arm 52, the distal end of which is articulated to a link member 53, the distal end of which carries the contact

element 21. The said articulation between link 53 is such that link 53 can be turned a slight extent to change the radial distance of contact element 21 from the spindle 9; the securing is then made fast, so that the lever arm 52 and link 53 are rigidly connected to be turned as a unit by the spindle 9.

We claim:

1. A control device comprising a pair of electrically conducting segments separated by a gap having a varying width; a spindle rotatively supported in a fixed relation to the segments and concentrically therewith; a contact arm slidably engaging the segments; a means to support the proximal end of the contact arm on the spindle; and a means to vary the radial length of the contact arm for causing the contact arm to engage the gap at a point of selected width.
2. In a device of the class described in combination; a pair of electrically conducting members on the base separated by a gap having varying width; a spindle rotatively supported in a fixed relation to the segments and concentrically therewith; a flange on the spindle; a contact arm 25 adjustably secured at its proximal end to the flange and slidably engaging the conducting members; and means to secure the contact arm on the flange in radially adjustable positions for causing the contact arm to pass over the gap at a point 30 of its width corresponding to the radial adjustment of the contact arm.
3. A control device comprising a pair of electrically conducting segments separated by a gap having a varying width; a spindle rotatively supported in a fixed relation to the segments and concentrically therewith; a contact arm; a flange on the spindle; means to adjustably support the proximal end of the contact arm on the flange for varying the effective radial length of the contact arm; and a contact element at the end of the contact arm slidably engaging the conducting segments, the contact element engaging the gap at a width corresponding to the radial adjustment of the contact arm.
4. A control device comprising an insulating base; a pair of electrically conducting segments on the base separated by a gap having a varying width; a spindle rotatively supported in a fixed relation to the segments and concentrically therewith; a contact arm, a flange on the spindle, the contact arm having a bifurcated proximal end supported on the flange; a contact element at the distal end of the contact arm slidably engaging the conducting segments; and a means to secure the contact arm on the flange in radially adjustable positions for causing the contact element to pass over the gap at the desired width thereof.
5. In a device of the class described, in combination, a spindle; an insulated disc rotatively mounted on the spindle; a pair of electrically conducting segments supported on the base, the adjacent ends of said segments being separated by a gap having a varying width; a flange secured to said spindle; a contact arm having a contact element at its distal end slidably engaging the segments; the proximal end of the contact arm being bifurcated to provide a central recess forming a pair of fingers having elongated slots, the said contact arm being mounted on the said flange with the said spindle received in the central recess of the contact arm; a pair of screws received in the said elongated slots for securing the contact arm to the flange in a selected radial position; the contact element thereby engaging the gap at

7 a width corresponding to the radial adjustment of the contact arm.

6. In a device of the class described, in combination, an insulated base; a pair of electrically conducting members on the base separated by a gap having a varying width; a spindle rotatively supported on the base in a fixed relation to the members and concentrically therewith; a contact arm adjustably secured at its proximal end on the spindle and slidably engaging the conducting members; a means to vary the radial effective length of the contact arm for causing the contact arm to pass over the gap at a width corresponding to radial length of the contact arm; a conducting plate supported on the base having different width at different radial distances; a second contact arm slidably engaging the contact plate secured to the spindle; and a means for varying the radial effective length of the second contact arm for causing the second contact arm to pass over the plate at a width corresponding to the radial length of the second contact arm.

7. A contact device comprising an insulating base; a pair of electrically conducting members

8 on the base separated by a gap having a varying width; a spindle rotatively supported in a fixed relation to the members; a contact arm constituted by two portions pivotally joined together; a means for securing the two arm portions in a selected relative angular position to each other for varying the effective radial length of the contact arm; a means to secure the proximal end of the inner arm portion to the spindle, the distal end of the outer arm portion slidably engaging the conducting members and passing over the gap at a width corresponding to the angular position of the second portion relative to the first portion.
